ALBERT B. MEGRAW, OF MERIDEN, CONNECTICUT, ASSIGNOR TO THE MILLER COMPANY, OF MERIDEN, CONNECTICUT, A CORPORATION OF CONNECTICUT

LIGHTING FIXTURE

Application filed April 23, 1927. Serial No. 185,967.

The present invention relates to a lighting fixture, and is more particularly directed to a semi-indirect lighting fixture for general illumination.

5 The present invention contemplates a lighting fixture in which the suspended parts of the fixture are so arranged that they may be readily disconnected from the lead wires, so as to facilitate installation of the fixture, removal or change of the fixture, and refinish 10 or cleaning the fixture.

The present invention contemplates a fixture in which a plurality of lamp socket supporting arms extend downwardly 15 through a central hole in a large toroidal shaped glass shade so as to support the lamp sockets underneath the shade to position lamp bulbs inside the shade. This provides a semi-indirect lighting fixture in which the 20 lamps are concealed by the glass shade.

A further object of the invention is to provide a chandelier wherein an annular glass shade, which houses a plurality of electric lamps but not the lamp supporting arms, 25 may be readily removed from the supports when the fixture is detached from its supports.

Another object of the invention is to provide 30 a chandelier wherein a plurality of lamps extend downwardly and outwardly from a body and support a glass shade which shade maintains the arms in proper position relative to one another.

35 A further object of the invention is to provide a lighting fixture which can be detachably supported from suspending means and at the same time detachably electrically connected to the fixture supply wires.

40 Other and further objects of the invention will appear as the description proceeds.

The accompanying drawings show, for 45 purposes of illustrating the invention, one of the many possible embodiments in which it may take form, it being understood that the drawings are illustrative of the invention rather than limiting the same.

In these drawings:

50 Figure 1 is a diagrammatic elevational view showing the fixture adjacent the lower

end of a supporting shade but separated from it;

Figure 2 is an enlarged elevational view of parts of the fixture, with parts in section;

Figure 3 is a still further enlarged view of 55 the parts taken on the line 3—3 of Figure 2; and

Figure 4 is an inverted plan view of the fixture.

When the lighting fixture contemplated by 60 the present invention is made up in the form of a chandelier for house and store lighting, it will be supported on some form of suspension element such as a rod, cord, or chain. As shown in Figure 1, the fixture is provided 65 with a loop 10 carried at the lower end of a fixture chain 11. The wiring for the fixture is carried down along the chain in the usual manner and passes through a hole in the loop. The lower end of the loop 10 70 is threaded as indicated at 12, in Figure 3, to support a hollow spindle 13, and a small hook or loop 14 is threaded into the lower end of the spindle. The lead wires from the fixture pass down through the spindle 13 and 75 loop 14 and are connected to plug receptacles 15. A cover member 16 is carried on the rim 17 of the spindle 13. This construction permits connecting up the shade and lead in 80 wires for the fixture with the house-lighting wires so that the house wiring may be inspected after the fixture has been connected to the circuit.

A body 18 is provided with a centrally arranged hook 19. As here shown, the structure for supporting this hook from the body is in the form of a spindle 20 passing through a hole 21 in the body member 18 and through a plate 22, and threaded into the lower end of the hook 19 as indicated at 90 23. The plate 22 rests on the flange of body member 18.

A plurality of tubular chandelier arms 24 are supported from the body member 18. As here indicated, the upper ends of these 95 arms are threaded to receive nipples 25 which pass through holes in the body 18. These nipples are locked in place by nuts 27 placed above and below the body member 18. The lower ends of the arms 24 are bent out- 100

wardly as indicated at 28 and each arm passes through the side wall of a socket holding cup 29. Side opening lamp sockets 30 are mounted in the socket holding cups and are fastened in place by ornamental knobs 31 threaded onto stems 32 carried in the lamp sockets.

The fixture wires 33 pass from the side opening lamp sockets 30 up through the tubular arms 24 and out into the chamber provided by the body member 18. The fixture wires 33 are brought together and connected to plugs such as illustrated at 34. The use of two receptacles 15 and two plugs 34 is preferred as it is possible to make this part of the fixture more compact than if an ordinary convenience receptacle were used. The chandelier is also provided with a glass shade 40. As indicated in the drawings, this shade is of U-shape or semi-circular cross section. The surfaces of the shade are formed as surfaces of revolution of a semi-circular (or substantially semi-circular) curve about the vertical axis of the shade. This provides an annular shade of toroidal shape. It is provided with regularly spaced holes 41 which are adapted to receive the upper ends 42 of the socket cups 29. The central hole or aperture 42 in the annular shade is sufficiently large to accommodate the fixture arms 24. It is also larger in diameter than the body 18.

In assembling the fixture, the glass shade is passed onto the metal parts of the fixture from above, and, when it has been brought to the position indicated in Figure 1, it will be supported on the flanges 43 on the socket cups 29. Whether or not it rests on the chandelier arms, would be a matter depending upon the shape of the arms.

The lower part of the fixture may be installed by inserting the hook 19 into the loop or hook 14 after which the plugs 34 may be inserted into the receptacles 15 and the cover 16 brought down into place against the body member 18. The weight of the fixture will be carried through the hook and loop while the wiring will be effectively installed and concealed. The fixture will hang true from the loop 14. It can be taken down at any time by going through the reverse operations. The glass shade will conceal the lamps 50 carried in the lamp sockets 30. It will reflect considerable of the light upwardly to the ceiling. It is preferably made of diffusing glass which produces a soft even glow around the fixture.

It is obvious that the invention may be embodied in many forms and constructions within the scope of the claims, and I wish it to be understood that the particular form shown is but one of the many forms. Various modifications and changes being possible, I do not otherwise limit myself in any way with respect thereto.

What is claimed is:

1. A chandelier having a plurality of lamps carried at the outer ends of chandelier arms, and an annular shade supported on the outer ends of the arms, the inner ends of the arms extending upwardly through the central hole in the shade. 70

2. A chandelier having a plurality of lamps carried at the outer ends of chandelier arms, an annular shade supported on the outer ends of the arms, the inner ends of the arms extending upwardly through the central hole in the shade, and a body member to which the upper ends of the arms are attached, the body being smaller than the hole in the shade, whereby the shade may be passed by the body. 75 80

3. A chandelier having a plurality of lamps carried at the outer ends of tubular chandelier arms, an annular shade supported on the outer ends of the arms, the inner ends of the arms extending upwardly through the central hole in the shade, a body member to which the upper ends of the arms are attached, the body being smaller than the hole in the shade, whereby the shade may be passed by the body member, fixture wires carried in the tubular arms, and plug contacts housed in the body member and connected to the fixture wires. 85 90 95

4. In a chandelier, a diffusing bowl of translucent material opening toward the top and of toroidal shape, vertical sections on radial planes being substantially semicircular both upper edges of the bowl being at substantially the same elevation, the bottom of the bowl having apertures, lamp sockets supported underneath the apertures, and lamps in the sockets, the upper inner part of the bowl shading the lamps and reflecting light outwardly above the outer upper edge. 100 105

5. A chandelier comprising a two part central assemblage, the upper part being in the form of a suspension element through which supply wires pass, the lower part being in the form of a body member adapted to support chandelier arms, the two parts carrying cooperative quick detachable devices to permit hanging the lower part from the upper part, chandelier arms fixedly carried by the lower part, lamp sockets carried by the arms, socket supply wires leading into the said lower part and connected to plug contacts, and cooperative receptacles carried by the supply wires whereby the electrical connections between supply wires may be made or broken when the lower part of the assemblage is hanging from the upper part. 110 115 120

6. A chandelier comprising a two part central assemblage, the upper part being in the form of a suspension element through which supply wires pass, the lower part being in the form of a body member adapted to support chandelier arms, the two parts carrying cooperative quick detachable de- 125 130

5 vices to permit hanging the lower part from the upper part, downwardly and outwardly extending chandelier arms fixedly carried by the lower part, lamp sockets carried by the arms, socket supply wires leading into the said lower part and connected to plug contacts, cooperative receptacles carried by the supply wires whereby the electrical connections between supply wires may 10 be made or broken when the lower part of the assemblage is hanging from the upper part, and an annular one piece glass shade carried by the outer ends of the chandelier arms, the shade being non-removable downward past the arms, but being removable upward past the lower part of the central assemblage when disconnected from the upper part thereof.

20 7. A semi-indirect lighting fixture comprising a two part central assemblage, means to hang the assemblage from the ceiling, the parts being provided with quick detachable devices to permit hanging the lower part from the upper part, lead-in wires carried 25 by the upper part of the assemblage, fixture arms, sockets and socket supply wires carried by the lower parts, cooperative plug receptacles and contacts carried by the wires placed between the parts of the assemblage 30 whereby the electrical connections between supply wires may be made or broken when the lower part of the assemblage is hanging from the upper parts, and an annular diffusing shade supported on the fixture arms and 35 removable upwardly only.

8. A chandelier comprising a hollow suspension element having a coupling at the lower end of the suspension element, lead wires passing through the suspension element and coupling and provided with receptacle contacts, a chandelier body and a hook carried by the body and cooperable with the upper coupling for detachably supporting the body from the suspension element, the body carrying plug contacts cooperable with the receptacle contacts.

9. A chandelier comprising a suspension element, a hook at the lower end of the suspension element, lead wires carried by the suspension element and extending below the hook and provided with receptacle contacts, a body, a lower hook carried by the body and cooperable with the upper hook for detachably supporting the body from the suspension element, a plurality of hollow arms fastened to the body, lamp sockets carried by the arms, and supply wires carried in the arms and provided with plug contacts cooperable with the receptacle contacts.

10. A chandelier comprising a hollow suspension element, a hook at the lower end of the suspension element, lead wires passing through the suspension element and hook provided with receptacle contacts, a body, a lower hook carried by the body and

cooperable with the upper hook for detachably supporting the body from the suspension element, a plurality of hollow arms fastened to the body, lamp sockets carried by the arms, and supply wires carried in the arms and provided with plug contacts cooperable with the receptacle contacts.

11. A chandelier comprising a hollow suspension element, a hook at the lower end of the suspension element, lead wires passing through the suspension element and hook and provided with receptacle contacts, a body, a lower hook carried by the body and cooperable with the upper hook for detachably supporting the body from the suspension element, a plurality of hollow arms fastened to the body, lamp sockets carried by the arms, supply wires carried in the arms and provided with plug contacts cooperable with the receptacle contacts, and an annular glass shade supported on the arms, the hole in the shade being larger than the body.

Signed at Meriden, in the county of New Haven and State of Connecticut, this 18 day of April, 1927.

ALBERT B. MEGRAW.
